(57) CLAIM

The ornamental design for a table tennis net holder, as shown and described.

DESCRIPTION

FIG. 1 is a top, front, left perspective view of a table tennis net holder, embodying my new design;

FIG. 2 is a top, front, right perspective view thereof;

FIG. 3 is a bottom, rear, left perspective view thereof;

FIG. 4 is a front view thereof, the rear view being a mirror image thereof;

FIG. 5 is a left side view thereof;

FIG. 6 is a right side view thereof;

FIG. 7 is a top plan view thereof; and,

FIG. 8 is a bottom plan view thereof.

The broken lines shown in the figures depict portions of the table tennis net holder that form no part of the claimed design.

1 Claim, 6 Drawing Sheets
